UNITED STATES PATENT OFFICE.

ALBERT F. VORCE, OF GRAND RAPIDS, MICHIGAN, ASSIGNOR OF ONE-THIRD TO WARREN H. STANSBERRY AND ONE-THIRD TO EDWIN H. WITHERELL, BOTH OF GRAND HAVEN, MICHIGAN.

MACHINE FOR MAKING CROCHET-NEEDLES.

1,239,851.

Specification of Letters Patent. Patented Sept. 11, 1917.

Application filed June 12, 1916. Serial No. 103,263.

To all whom it may concern:

Be it known that I, ALBERT F. VORCE, a citizen of the United States of America, residing at Grand Rapids, in the county of Kent and State of Michigan, have invented certain new and useful Improvements in Machines for Making Crochet-Needles; and I do hereby declare the following to be a full, clear, and exact description of the invention, such as will enable others skilled in the art to which it appertains to make and use the same.

This invention relates to a machine for making crochet needles. It is the object and purpose of the invention to provide a mechanism in which a rod or bar of metal may be placed, the machine operating to turn one end of the bar around a suitable die and shape it into a hook such as is necessary to complete a crochet needle. A further object of the invention consists in the provision of a simple and economically constructed machine for attaining the result stated and one in which the working parts of the machine that act upon the bar or rod are compelled to pass through certain movements positively in the bending and forming of the end of the bar into a hook. Other objects and purposes together with novel details of structure for attaining the same will appear as understanding is had of the invention, reference being had to the accompanying drawings which illustrate a preferred embodiment of the same.

35 In the drawings,

Figure 1 is a side elevation of the machine.

Fig. 2 is a similar view from the opposite side of the machine.

40 Fig. 3 is an end elevation.

Figs. 4 and 5 are side elevations, from opposite sides, of the mechanism which acts upon the bar to form it into a crochet needle, such views being enlarged to better show the construction.

Like reference characters refer to like parts throughout the several views of the drawings.

In the construction illustrated, an elongated metal strap 1 is provided which may be attached to a table or other support 2. Projecting upwardly from one end of this strap is a block 3 through which a shaft 4 passes. It is contemplated in the use of

this invention that a plurality of machines shall be placed upon and attached to table 2, the drive shaft 4, which may be driven in any suitable manner, passing through all of the blocks 3. A pinion 5 secured to the shaft near the block meshes with a gear 6 the diameter of which, preferably, is three times that of the driving pinion 5, though any other suitable size of gear may be used. A stud 7 is secured to and projects from one face of the gear 6.

At the opposite end of member 1 a support is secured comprised of a horizontal base 8 having uprights 9 and 10 at the ends which are each connected by a table 11 divided at one end to make spaced apart legs 12 between which an irregular shaped member 13 is adapted to move. Member 13 is pivotally connected adjacent its lower end to the forward end of a bar 14 suspended by means of links 15 and 16 from the table 11. A coil spring 17 attached to the bar 14 and to the upright 10 has a normal tendency to pull this bar toward the upright and retract the member 13 to its lowermost position, as that shown in Figs. 4 and 5. A curved slot 18 is cut in the member 13, a pin 19 supported between the legs 12 passing through the slot and limiting the movement of bar 14.

A pin 20 which is used to pivotally connect the lower ends of links 16 and the bar 14 projects a distance beyond the links and enters a slot 21 formed in one end of an operating bar 23, the pin being provided with a head 22 which serves to keep the bar from disengagement therefrom. The operating bar extends alongside gear 6 and has a portion cut away on its under side adjacent its opposite end as indicated at 24 and is also formed with a concave notch 25 in which the stud 7 may seat. When stud 7 is at its uppermost position on the gear the bar 14 is in its normal position but during the first quarter turn of the gear in a counter clock wise direction said bar is carried along with the stud to the position shown in Fig. 1, thereby elevating the irregular shaped member 13 as shown. With the succeeding quarter turn spring 17 returns the parts to normal position after which they remain at rest until gear 6 has completed a revolution, it being apparent that the stud 7 traverses the underside of the bar 23.

until it strikes the shoulder 24^a whereupon bar 23 is moved, the pin 20 passing along slot 21 and into a recess 21^a at the end of the slot shown in Fig. 1, the recess permitting the bar to drop slightly and be held while the stud 7 returns to the recess at 25.

Projecting upwardly from the table 11 is a plate 26 serving as a support for a die 27 pivotally mounted on the face of the plate 26 and having an inclined upper surface so that the die at its free end comes to a point. A cam 28 lies directly above the inclined surface of the die being mounted on a pin, which extends through the plate 26, the pin 15 at the opposite side of the plate having a lever 29 fixed thereto. The lever 29 at a point somewhat above at its lower end has a concave recess 30 cut therein which is adapted to be engaged by a pin 31 projecting laterally from bar 23. Also the irregular shaped member 13 has a right angular notch 32 cut therein which in the normal position of the various parts of the mechanism lies directly in front of the end of die 27. Below the notch 32 the irregular shaped member has a surface 32^a which co-acts with the die in completing the hook as will be later described.

A stop 33 is adjustably secured to the end 30 of table 11 directly above upright 10 and is right angular in cross section one leg 33^a paralleling table 11 while the other crosses it. The adjustment is effected by means of a screw 34 passing through the slot 35 in stop 33 and entering the table 11.

A rod of metal from which the needle is to be formed is laid upon the table 11 one end contacting with the stop 33 while the other enters the notch 32 in member 13 40 passing underneath the die 27. As gear 6 turns the first movement bends the end of the bar around the end of the die it being thereafter engaged by the surface 32^a of the member 13 and forced against the die. 45 It will be apparent that as soon as bar 23 is carried lengthwise as the gear 6 rotates pin 31 is moved away from lever 29 permitting this lever to drop through gravity cam 28 binding tightly against the upper inclined side of die 27 and holding the metal rod firmly in place during the operation of the mechanism. After the hook is completed the further movement of the gear 50 releases the mechanism spring 17 returning the parts to normal position as shown in Figs. 3 and 4, whereupon the die is released for removal of the crochet needle. The mechanism therefor remains at rest during practically one half of the revolution of gear 6, during which time the completed crochet needle may be removed from the machine and another rod placed in it for the next operation. If at any time it is desired that the hook forming mechanism shall be 55 at rest for a time this can be easily attained

by positioning pin 31 in a notch 36 cut in the lever 29 below the recess 30 heretofore described, this serving to lift the end of operating bar 23 out of engagement with stud 7. In this manner a plurality of machines may be driven by one shaft 4 yet any one of the machines be disconnected from the driving mechanism and permitted to be at rest while the rest of the machines are in operation.

The operator of the machines inserts the rods one after another in the machine with each revolution of the gear 6. This gear is driven at a comparatively low speed as the drive shaft 4 makes three complete revolutions for each revolution of the gear and plenty of time is given for the removal of the crochet needles and insertion of the rods from which the needles are made. When a hook has been formed on a needle bar it is necessary thereafter merely to slightly grind the hook thus formed to complete the finished product.

I claim:—

1. In combination, a support, a table carried thereby, a bar suspended from the table, a die having a sharp end located above the end of the table, a member connected to the end of the bar and mounted to turn upwardly and around the end of the die on longitudinal movement of the bar, means to periodically operate the bar, and means automatically operated with the bar operating means to clamp a needle rod under the die and said member.

2. In combination, a table, a support therefor, a plate projecting upwardly from the table, a die having an inclined upper face pivotally mounted on the plate, a cam 105 rotatively mounted on the plate above the inclined face of the die, a lever connected with the cam and operating normally by gravity to force said cam against the die, a bar suspended from the table, a member connected to one end of the bar adapted on longitudinal movement thereof in one direction to turn around the end of the die, an operating bar connected to said bar, means to give a reciprocatory movement to the 110 operating bar, and a pin on said operating bar adapted in one position to engage against the lever and release the die.

3. In combination, a mechanism for turning a hook at one end of a needle rod, including a table, a bar suspended from the table, means operated by movement of the bar for turning said hook, a member mounted for rotation, means to rotate said member, a pin projecting from the member, a pin projecting from the bar, and a bar provided at one end with a slot having an enlarged portion at one end and with a longitudinal recess cut therefrom on its under side at the other end interposed between 125

said pins, the pin on the rotating member being received in the recess, and the pin on the first bar entering into said slot.

4. In combination, a table, a member having an inclined upper face and a pointed end pivotally mounted above the table, a cam rotatively mounted above the inclined face of the member, a lever secured to said cam and normally dropping by gravity to there-
10 by turn the cam against the member and force it toward the table against a needle bar held between the member and table, means for turning one end of said bar around the pointed end of the member to
15 turn a hook, and means for engaging with the lever to turn the cam and release the member after the hook is formed.

5. In combination, a table, a member having an inclined upper face and a pointed end pivotally mounted above the table, a cam rotatively mounted above the inclined face of the member, a lever secured to the cam and normally actuated by gravity to turn the cam against said member and thereby
25 hold a needle bar interposed between the member and table against movement, a de-
vice for turning one end of said needle bar around the pointed end of the members to make a hook, an operating bar, mechanism
30 connecting said bar with said hook turning device, means for periodically reciprocating the operating bar, and means on said bar for engaging against the lever and turning the cam to release said member after the hook is
35 formed.

6. In combination, a table, a member having a pointed end pivotally mounted at its opposite end and located above the table, links suspended from the table, a bar carried
40 at the lower ends of the links, a hook turning member pivotally connected to one end of the bar, means to reciprocate the bar, and means to guide the hook turning member over the pointed end of the first mentioned
45 member.

7. In combination, a table, a member having a pointed end pivotally mounted at its opposite end and located above the table, links suspended from the table, a bar carried
50 at the lower ends of the links, a hook turning member pivotally connected to one end of the bar, said hook turning member

being provided with a curved slot, a pin carried a short distance from one end of the table passing through the slot and serving 55 to guide the movements of said hook turning member over the pointed end of the first mentioned members and means to periodically reciprocate the bar.

8. In combination, a table, a member hav- 60 ing a pointed end pivotally mounted at its opposite end and located above the table links suspended from the table, a bar carried at the lower ends of the links, a hook turning member pivotally connected to one 65 end of the bar, said member being provided with a substantially right angular notch normally positioned at the pointed end of the first mentioned member, means to guide said hook turning member over the pointed 70 end of the first member to turn on a bar held between said first member and table, means to hold said bar during the hook turning operation, and means to release the bar after formation of the hook. 75

9. In combination, a table, a member hav-
ing an inclined upper face and a pointed end pivotally mounted a short distance above the table, a cam rotatively mounted above the inclined face of the member, a 80 lever secured to the cam and normally dropping by gravity to thereby turn the cam against the member and force it toward the table against a needle bar placed between the member and table, a bar suspended be-
low the table, a hook turning device pivot-
ally connected to one end of the needle bar and adapted in its movement to turn a hook over the pointed end of said member on the end of said needle bar, a member mounted 90 for rotation, means to rotate said member, a pin projecting from said rotating member, a pin projecting from the bar suspended be-
low the table, and a second bar provided ad-
jacent one end with a slot having an en- 95 larged portion at one end and with a long recess cut therefrom on its under side at the other end interposed between said pins, the pin on the rotating member being received in the recess, and the pin on the first bar en- 100 tering said slot.

In testimony whereof I affix my signature.

ALBERT F. VORCE.
